(57) **CLAIM**

The ornamental design for a portable information reading terminal, as shown and described.

DESCRIPTION

FIG. 1 is a perspective view showing our new design for a portable information reading terminal;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a front view illustrating the portable information reading terminal of the present invention in its environment of use; and,

FIG. 9 is a perspective view illustrating the portable information reading terminal of the present invention in its environment of use.

The portions shown in broken lines are solely for the purpose of illustrating context and environmental structures only and form no part of the claimed design.
